CLAIM

The ornamental design for a camera, as shown and described.

DESCRIPTION

FIG. 1 is a front, left side, top perspective view of a camera showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

(Continued)

The broken lines in the drawings illustrate portions of the camera that form no part of the claimed design.

1 Claim, 4 Drawing Sheets
